UNITED STATES PATENT OFFICE.

ALMERN B. WALTERS, OF PHILADELPHIA, PENNSYLVANIA.

LOCK FOR SLIDING DOORS.

SPECIFICATION forming part of Letters Patent No. 276,941, dated May 1, 1883.

Application filed January 8, 1883. (Model.)

To all whom it may concern:

Be it known that I, A. B. WALTERS, a citizen of the United States, residing at No. 132 South Fifteenth street, in the city and county of Philadelphia, and State of Pennsylvania, have invented a new and useful Lock for Sliding Doors, of which the following is a specification.

My invention relates to improvements on locks for sliding doors to hold the door closed by a fastening in the rear, with projecting catches fastened to a movable piece and catching into pockets in the side of the car. The said piece is swung on two journals, one in each end, said journals having bearings in the stile running longitudinally on top and bottom of door, and it is fastened by any kind of lock or catch. I also include projections fastened in the front edge of the door, and fitted in mortises in the jam. These and the lock hold the door, even if all other guides and fastenings are broken off.

The details of construction and operation of the several parts will be more fully set forth hereinafter, and shown in the accompanying drawings, in which—

Figure 1 is a side elevation of a car-door with my locking device attached thereto, the door being closed and locked; and Fig. 2, a horizontal section on the line A B, Fig. 1.

Referring more particularly to the drawings, C represents the side of the car, provided with suitable side rails, E, which have guides F, secured to and projecting above and below the rails. The door-stiles H are provided at the ends with trunnion-bearings for the trunnions L, which also have bearings in the ends of a movable door-securing piece or section, K. This piece K turns on the trunnions L, and is provided with two or more projecting lugs, M, rigidly secured to the piece K. These lugs or projections are curved, as shown, and are adapted to enter pockets or recesses N in the side of the car. The recesses are undercut to conform to the curved portion of the lugs. The door is further provided with two or more dowel-pins, J', which enter dowel-openings in the vertical piece J, secured to the side of the car. The door is provided with a suitable hasp and staple, O, and the door held or secured by a suitable lock. When the door is

closed the lugs M on the section K are held in the recesses N, and the dowel-pins are in the openings in piece J. When it is desired to open the door it is only necessary to swing or turn the section K outwardly on the trunnions. This carries away the lugs M from engagement with the side of the car, and the door is then free to be moved along in the guides F. Thus it will be seen that the door will remain closed until the section K is swung outwardly, no matter whether the rails F and the hasp and lock are removed or not. The door is secured and kept from swinging outwardly at the end opposite the section K by means of the dowel-pins J. In alterations of old cars to receive my locking device it is only necessary to fasten a lug to the sides of the door to receive the trunnion L.

Having thus described my invention, what I claim is—

1. In combination with the side of a car or other structure having recesses or pockets N at the side of the door, a sliding door provided with a hinged or pivoted section at its vertical edge, said section provided with projecting arms, as M, on the face adjacent to the car-body, adapted, when the door is closed, to enter the pockets or recesses N, as described. 75
2. In combination with the side of a car or other structure provided with recesses or pockets N at the side of the doorway, a sliding door provided with a hinged or pivoted section at its vertical edge, said section provided with projecting arms M on the face adjoining the car-body, adapted to enter the recesses N when the door is closed, and a lock for locking said door-section, as described. 80
3. In combination with the side of a car or other structure provided with undercut recesses N at the side of the doorway, a sliding door provided with a hinged or pivoted section at its vertical edge, said section provided with projecting arms M on the face adjoining the car-body, adapted to enter the recesses N when 85 the door is closed, and a lock for locking said door-section, as described. 90
